WASHABLE RUFFLED WINDOW CURTAIN

Helen F. Gundlach, Ebenezer, N. Y.

Application November 4, 1948, Serial No. 58,299

6 Claims. (Cl. 160—348)

1

This invention relates to window curtains, and more particularly to a washable ruffled window curtain.

Ruffled curtains are in common use in homes and are desirable because of the soft and pleasant appearance produced by them. However, the washing and ironing of ruffled curtains, as heretofore constructed, has constituted such a drudge for many housewives that they sent the curtains to a commercial laundry rather than subject themselves to the task of washing and painstakingly ironing the curtains.

Accordingly, a primary object of the invention is to provide an attractive, ruffled and flounce window curtain which does not require ironing after being washed.

Another important object is to provide such a window curtain which can be easily and readily washed and restored to a condition for rehanging and therefore the housewife is encouraged rather than discouraged to wash her curtains at home rather than send them to a commercial laundry.

Another object is to provide such a curtain which is easy to put up and take down before and after washing the curtain.

Another object is to provide such a curtain which can be adjusted to fit windows of different heights.

Another object is to provide such a curtain which is simple in construction and hence easy and inexpensive to manufacture.

Other objects and advantages of the invention will be apparent from the following description and accompanying drawings wherein:

Fig. 1 is an elevational view of the front sides of a pair of curtains embodying the present invention and being shown, as hanging from a conventional curtain rod, the curtain at the right being shown in its finally adjusted ruffled form and the curtain at the left being shown in a draped condition preparatory to adjusting the same to its ruffled condition.

Fig. 2 is an enlarged fragmentary sectional view taken on line 2—2, Fig. 1.

Fig. 3 is an enlarged fragmentary sectional view taken on line 3—3, Fig. 1.

Fig. 4 is an enlarged fragmentary elevational view of the lower left hand corner portion of the ruffled curtain shown at the right in Fig. 1.

Fig. 5 is a perspective elevational view of the curtain shown at the right in Fig. 1 and illustrating the manner in which the curtain can be stretched for drying.

Fig. 6 is a fragmentary elevational view similar to Fig. 4 and illustrating a modified form of curtain construction.

Fig. 7 is a sectional view thereof taken on line 7—7, Fig. 6.

A preferred form of curtain embodying the present invention is illustrated in Figs. 1 through 5 and comprises an elongated rectangular piece

2

of any suitable light-weight, permanently starched or sized, finely woven and transparent fabric used for window curtains, such as permanent stiff finish cotton or rayon marquisette or other suitable net fabric, and having hems 10 and 11 at the opposite transverse narrow ends, these hems being formed by turning over the marginal portion of the curtain piece to provide a loop and securing the edge of the turned over portion to the main body of the curtain in any suitable manner as by a line of stitching. The construction of such hems is well-known in the art of curtain manufacture. As illustrated, the curtain hangs vertically from a conventional curtain rod 12 of any suitable type, this curtain rod passing through the top hem or loop which is designated by the numeral 10, the bottom hem being designated by the numeral 11.

A pair of elastic cords, threads or strands 13 and 14 are arranged on the fabric piece adjacent the vertical longitudinal edges thereof and extend the full length thereof and divide the curtain into three sections 15, 16 and 17, the sections 15 and 17 being relatively narrow marginal strips and the central section 16 being a wider strip between these marginal strips. The elastic cords 13 and 14, as best shown in Figs. 2 and 3, are preferably connected to the curtain fabric by weaving these cords in and out through the fabric in substantially a straight line parallel to the vertical edges of the curtain, the upper end of each such elastic cord being suitably anchored or secured to the curtain adjacent the upper end thereof and the lower end of each of these cords emerging from a place adjacent the lower edge of the bottom hem 11. As shown in Fig. 2, the upper end of each elastic cord, as represented by the cord 13, is preferably formed into a loop lying against the inner surface of the top hem 10 and suitably stitched thereto. However, any other suitable manner of anchoring the upper end of the elastic cords 13 and 14 to the curtain fabric can be employed. In Fig. 2, the elastic cord 13 is illustrated as being straight and as passing through the adjacent curtain fabric at generally uniformly spaced intervals so as to provide stitches. The stitch of the elastic cords is similar to a simple running or tack stitch as used in basting although the length of the stitches or the exposed lengths of elastic cords on the front and back sides of the curtain is preferably shorter than that usually employed in basting.

A feature of the invention is to provide a soft and graceful appearing curtain in which the central section 16 is festooned or draped in a series of superposed upwardly facing curved bends or folds and also in which the marginal sections 15 and 17 are ruffled, as shown at the right in Fig. 1.

To arrange the straight and flat hanging curtain shown at the left in Fig. 1 in the festooned and ruffled form shown at the right in Fig. 1, the

curtain fabric is pushed upwardly and shirred on the elastic cords 13 and 14 so as to gather the curtain fabric on these cords and make it stand outwardly therefrom, as illustrated in Fig. 3. During this shirring operation the elastic cords 13 and 14 are maintained in an unstretched condition. This can be done by holding the exposed lower ends of the elastic cords firmly in one hand while with the other hand the fabric is pushed upwardly on the cords toward the top hem. The gathers in the curtain fabric can be adjusted to give the curtain a uniform appearance from its top to its bottom and these gathers are maintained in their adjusted positions due to the frictional engagement between the elastic cords and the light-weight fabric. The gathers formed in the curtain fabric along the elastic cords generate the ruffles in the marginal sections 15 and 17 and also the festoons in the central section 16. It has been found that a length of flat hanging curtain adjusted in this manner to have a final shirred length of about one-half its original flat length provides a soft appearing and highly attractive curtain. However, the curtain can be adjusted to any length and fullness desired.

After the curtain has been so shirred or gathered on the unstretched cords 13 and 14, the lower ends thereof are anchored to the bottom of the curtain. As best shown in Fig. 5, this is preferably accomplished by tying a knot 18 in each of the elastic cords at the place where these cords emerge from the lower edge of the bottom hem 11 and cutting off the tail or portion of the cords below the knots 18. Instead of cutting off the elastic cords, their exposed ends can be tucked into the ends of the bottom hem 11 and thus hidden from view. Further, any other suitable manner of securing the lower edge of the curtain fabric to the elastic cords can be employed. For purposes of illustration, the size of the knots 18 and also the thickness of the cords 13 and 14 is exaggerated.

It will thus be seen that an attractive curtain having a festooned central section with ruffled borders extending along the opposite vertical sides thereof is provided. A pair of such curtains is generally provided at each window although a single curtain may be desired. It is preferred to avoid gathering the curtain in a horizontal direction on the curtain rod 12 as this tends to destroy the attractive festooned effect of the central section. The elastic cords 13 and 14 preferably have the same color as the curtain fabric material so as to be inconspicuous. If desired the top of the curtain can be covered with a separate ruffled valance (not shown) on a separate curtain rod (not shown), as several rods generally are purchased in a set of conventional curtain rods. Also a ruffled band or strip (not shown) can be used to tie back the curtain intermediate its top and bottom to give the common tie back arrangement employed with ruffled curtains. Such valance and tie back form no part of the present invention and hence have not been illustrated.

A very important feature of the invention is that a curtain constructed and hung as described above can be readily taken down, washed and dried and restored to a condition for rehanging without requiring the curtain to be ironed. The ironing of the curtain is eliminated by pulling the elastic cords to permit the curtain to be stretched flat and drying the curtain when in this flat and stretched condition. This can be achieved, as illustrated in Fig. 5, by hanging the cur-

tain from two straight bars or rods 19 arranged in the hems 10 and 11 and projecting outwardly therefrom and supported in any suitable manner in substantial parallelism, and placing a weighted round bar or rod 20 in the bight of the curtain. The rod 20 should be sufficiently heavy to stretch the elastic cords to permit the curtain to assume a flat condition in which the curtain will dry smooth without wrinkles. After the curtain is dry the rods 19 and 20 are removed to permit the elastic cords 13 and 14 to contract in length and thus restore the curtain to its shirred form. The curtain can then be rehung on the curtain rod 12 as shown at the right in Fig. 1. It has been found that this contraction of the elastic cords produces a uniform shirred effect and very little final adjustment of individual gathers is required.

The reason the curtain is illustrated in Fig. 5 as being looped or stretched double for drying is that a curtain embodying the invention and provided for the customary full length window found in the average home of today would be too long to hang stretched in a single straight panel. However, if space permits the stretching of the curtain into a single straight panel, the folding or looping of the curtain as illustrated in Fig. 5 can be eliminated and a weighted rod can be placed in the bottom hem 11 with the curtain supported on a rod extending through the top hem 10. Also instead of employing the rods 19 and 20 any other suitable form of curtain stretcher or device for holding the curtain in a stretched flat condition when drying can be employed.

Instead of weaving the elastic cords 13 and 14 in and out through the curtain fabric, the modified construction shown in Figs. 6 and 7, can be employed. As shown in Figs. 6 and 7, a small vertically running tube or hem 21 is provided in the curtain fabric adjacent each vertical side thereof. This tube or hem 21 extends the full length of the curtain and is preferably formed by folding the curtain upon itself to provide a loop and stitching the contacting ends of the loop together. Within each such tube or hem 21 so formed is arranged an elastic cord 22 similar to the elastic cords 13 and 14. The ends of the elastic cords 22 can be secured to the curtain in the same manner described for the form of the invention shown in Figs. 1-5. The modified form of curtain shown in Figs. 6 and 7 can be shirred in the same manner as described for the curtain shown in Figs. 1-5.

If in wearing and laundering, the elastic cords in either illustrated form of the invention gradually lose their elasticity, any permanent stretch in the cords can be taken up by forming the knots 18 farther up the cords and tucking the portion of each cord below its knot into the bottom hem 11. Such surplus cord is never cut off since it will be needed in laundering the curtain to permit the curtain to be stretched flat.

From the foregoing it will be seen that the present invention provides an attractive ruffled curtain which is easy to hang and take down and most important need not be ironed after washing. Further, the curtain is simple in construction and inexpensive to manufacture.

I claim:

1. A washable window curtain which requires no ironing, comprising an elongated rectangular piece of finely woven light-weight fabric, a hem at one of the narrow ends of said fabric piece for receiving a curtain rod on which the curtain

hangs, and a pair of unstretched elastic cords secured to said fabric piece adjacent the longitudinal edges thereof and fastened at opposite ends to both of said narrow ends of said fabric piece, the fabric being gathered on said elastic cords to provide a festooned central section between said elastic cords and a ruffled border along each of said longitudinal edges, said elastic cords being adapted to be stretched to the full length of said fabric piece when in an ungathered condition to permit said fabric piece to be stretched flat for drying of the curtain after being washed.

2. A washable window curtain which requires no ironing, comprising an elongated rectangular piece of finely woven light-weight fabric, a hem at one of the narrow ends of said fabric piece for receiving a curtain rod on which the curtain hangs, and a pair of unstretched elastic cords secured to said fabric piece adjacent the longitudinal edges thereof and fastened at opposite ends to both of said narrow ends of said fabric piece and dividing said fabric piece into a central section and relatively narrow marginal sections along opposite longitudinal sides of said central section, the fabric being gathered on said elastic cords to festoon the fabric in said central section and to ruffle the fabric in said marginal sections, said elastic cords being adapted to be stretched to the full length of said fabric piece when in an ungathered condition to permit said fabric piece to be stretched flat for drying of the curtain after it is washed.

3. A washable window curtain which requires no ironing, comprising an elongated rectangular piece of finely woven light-weight fabric, a hem at one of the narrow ends of said fabric piece for receiving a curtain rod on which the curtain hangs, and an unstretched elastic cord woven in and out through said fabric piece along a substantially straight line parallel to but spaced inwardly of each of the longitudinal edges of said fabric piece thereby dividing said fabric piece into a central section and relatively narrow marginal sections on opposite longitudinal sides of said central section, the end of each of said elastic cords adjacent said hem being fastened to said fabric piece and the opposite end of each of said elastic cords being fastened to the narrow end of said fabric piece remote from said hem, the fabric being gathered on said elastic cords to festoon the fabric in said central section and to ruffle the fabric in said marginal sections, said elastic cords being adapted to be stretched to the full length of said fabric piece when in an ungathered condition to permit said fabric to be stretched flat for drying of the curtain after it is washed.

4. A washable window curtain which requires no ironing, comprising an elongated rectangular piece of finely woven light-weight fabric, a hem at one of the narrow ends of said fabric piece for receiving a curtain rod on which the curtain hangs, a fabric tube on said fabric piece adjacent each of the longitudinal edges thereof and extending in a substantially straight line the full length of said fabric piece and dividing said fabric piece into a central section and relatively narrow marginal sections on opposite longitudinal sides of said central section, and an unstretched elastic cord arranged in each of said fabric tubes and

fastened at its opposite ends to said fabric piece, the fabric being gathered on said elastic cords to festoon the fabric in said central section and to ruffle the fabric in said marginal sections, said elastic cords being adapted to be stretched to the full length of said fabric piece when in an ungathered condition to permit said fabric to be stretched flat for drying of the curtain after it is washed.

5. A washable window curtain which requires no ironing, comprising an elongated rectangular piece of finely woven lightweight fabric, a hem at one of the narrow ends of said fabric piece for receiving a curtain rod on which the curtain hangs, a continuous hem formed in said fabric piece adjacent each of the longitudinal edges thereof and extending in a substantially straight line the full length of said fabric piece and dividing said fabric piece into a central section and relatively narrow marginal sections on opposite longitudinal sides of said central section, and an unstretched elastic cord arranged in each of said continuous hems and fastened at its opposite ends to said fabric piece, the fabric being gathered on said elastic cords to festoon the fabric in said central section and to ruffle the fabric in said marginal sections, said elastic cords being adapted to be stretched to the full length of said fabric piece when in an ungathered condition to permit said fabric to be stretched flat for drying of the curtain after it is washed.

6. A washable window curtain which requires no ironing, comprising an elongated rectangular piece of finely woven light-weight fabric, a hem at one of the narrow ends of said fabric piece for receiving a curtain rod on which the curtain hangs, and a pair of unstretched elastic cords secured to said fabric piece adjacent the longitudinal edges thereof and dividing said fabric piece into a central section and relatively narrow marginal sections along opposite longitudinal sides of said central section, the end of each of said elastic cords adjacent said hem being fastened to said fabric piece and the opposite end of each of said elastic cords emerging from the narrow end of said fabric piece remote from said hem, the fabric being adapted to be gathered along said elastic cords while unstretched to festoon the fabric in said central section and to ruffle the fabric in said marginal sections so that after securement of the free ends of said elastic cords to said fabric piece at their places of emergence therefrom, such effectively shortened unstretched elastic cords can be stretched to the full length of said fabric piece when in an ungathered condition to permit the fabric piece to be stretched flat for drying of the curtain after it is washed.
